F. H. MAYER

ELECTRIC SADIRON

Original Filed Oct. 18, 1922

Fred H. Mayer, ^{INVENTOR.}
By,
Atkins & Atkins,
ATTORNEYS.

Patented Nov. 30, 1926.

UNITED STATES PATENT OFFICE.

FRED H. MAYER, OF SALEM, OREGON.

ELECTRIC SADIRON.

Application filed October 18, 1892, Serial No. 595,288. Renewed June 7, 1926.

My invention relates particularly to sad-irons that are adapted to be heated by electricity, in which a plurality of independent heating circuits is provided, but in its broader aspect comprises a novel means of thermostatic control of a plurality of heating circuits for making and breaking circuit, whereby the life of the electric contacts is effectually prolonged, and whereby the intensity and consequent efficiency of the heating energy employed may be greatly augmented without the danger of burning out of the contacts to which ordinary thermostats are subject.

In respect to the means of thermostatic control, my invention consists in a thermostatic make and break connection, enclosed in circuit, within a sealed chamber in a de-oxygenized atmosphere.

What constitutes my invention will be hereinafter specified in detail and succinctly set forth in the appended claims.

In the accompanying drawing in which I illustrate my invention in present preferred form of embodiment,

Figure I is a side elevation partially in vertical section, of an electric sad-iron embodying my invention.

Figure II is a top plan view of the same with the top of the sad-iron removed.

Figure III is a section on the line III-III of Figure I.

Referring to the numerals on the drawing, 1 indicates, for example, a faced ironing member or base to which a suitable handle 2 is secured as through an intermediate cap or cover 3, which is preferably fastened as by screws 4 to a heat-conserving bifurcated member 5 which is in turn secured as by screws 6 to the base 1.

The member 5 may be in fact a two-part member, provided the two parts are relatively disposed one to the other so as, in effect, to constitute a bifurcated member whose sides are located in juxtaposition to and are substantially coextensive with the opposite outer edges of the base 1 which the member 5 surmounts. Whether the said member 5 be made in one or two pieces, provision should, in either case, be made for the junction of the sides at the front end of the base so as to constitute a massive heat conserving toe-piece to effect concentration of heat at the point where it is most needed.

In operative propinquity to the member 5, for the purpose of heating it, I provide,

preferably between said member and the base 1, the core 8 of an electric heating element. About the core is wound the heating wires or ribbons 9 and 10 of a pair of independent circuits. Both circuits derive electricity through leads 11 and 12 communicating with a line-wire switch socket 14 after the ordinary manner.

The circuit including the wire 9 is a constant one, dependent only upon supply of energy for its constancy. The circuit which includes the wire 10 is intermittent, being broken, whenever a critical temperature is reached, by a thermostat let into said circuit and enclosed within a case 16.

The purpose of the employment of a plurality of circuits is to provide a quickly efficient means of raising the temperature of the base 1 to a desired degree, and afterwards to hold that temperature, substantially, without danger of extending it and with good economy of electric energy in operating the device.

Hitherto an obstacle in the way of perfecting a practical instrument of the kind just described, had it been contemplated, existed in the fact that thermostats which would do the work demanded of them were short lived, owing to the quick decay, through oxidization, of the make and break contacts of the thermostat, in the performance of their required function.

An important feature of my invention consists in sealing a thermostat in a deoxygenized atmosphere, within an hermetically sealed case 16. By the term "deoxygenized" I designate any gaseous atmosphere or a vacuum which is lacking either entirely or substantially, in oxygen. Air deprived of its oxygen constituent would satisfy the definition, and attempt to enumerate the entire class connotation is deemed unnecessary.

The case 16 may be made of any suitable metal or material such as glass, for example. It is confined preferably with facility of detachment and insertion within the space between the legs or two parts of the member 5 as by a pillow 17 below it and disposed between it and the top of the base 1, coacting with a clip 18 screwed, for example, to the cap 3. The pillow 17 is preferably of a mass, extent, and substance which will facilitate the ready conduction and conservation of heat, and thereby render the switch delicately sensitive to changes of temperature in the base 1.

Within the case 16, the thermostat comprehends a pair of arms 19 and 20 provided with terminal contacts 21 and 22. One of the said arms, 19 for example, is made of composite metals after the ordinary manner of thermostats, and is adapted, whenever a predetermined or critical temperature is developed in the body of the arm, to cause the contacts 21 and 22 to separate, with the effect of breaking circuit through the wire 10, and thereby reducing the amount of electric energy to that supplied through the one circuit which includes the wire 9. The contacts 21 and 22 are made preferably of copper or other suitable and inexpensive material.

The purpose of using a plurality of circuits is to afford economy of electric energy in the use of the iron and to avoid excessive heating of the iron, it being feasible through action of my thermostat to hold an iron after it is once heated at desired temperature by comparatively small accretions of heat units.

The construction and arrangements of the member 5 affords conservation and advantageous distribution of heat communicated to it, while the disposition of the thermostat between the legs or parts thereof renders it readily responsive to changes of temperature in the iron.

What I claim is:

1. The combination with a member to be heated and members of a plurality of heating circuits in operative communication therewith, of a thermostatic control switch

in one of said circuits, sealed within a de-oxygenized atmosphere, substantially as set forth.

2. The combination with a sad iron base and its cover of a bifurcated substantially V-shaped heat-conserving member whose arms are located in juxtaposition to and substantially co-extensive with said base, an electric heating element substantially concealed between the arms of said member and base substantially as and for the purpose described, and thermostatic switch mechanism disposed between said arms.

3. The combination with a sad-iron base and its cover, of a bifurcated heat conserving member whose sides are located in juxtaposition to and are substantially coextensive with the said base, an electric heating element in operative disposition to the base and said member, a plurality of heating circuits in operative communication with said element, and in one of said circuits a thermostatic control switch sealed in a deoxygenized atmosphere and located within the bifurcated portion of said member.

4. The combination with a sad-iron base, and an electric heating element and its circuit making member in operative disposition to the base, of a thermostatic control switch in circuit with said member, and a heat conserving pillow operatively interposed between said switch and base.

In testimony whereof, I have hereunto set my hand.

FRED. H. MAYER.
